[57] CLAIM

The ornamental design for a measuring cup, as shown and described.

DESCRIPTION

FIG. 1 is a front elevational view of a measuring cup showing our new design;

FIG. 2 is a right elevational view thereof;

FIG. 3 is a top plan view thereof;

FIG. 4 is a rear elevational view thereof;

FIG. 5 is a bottom plan view thereof;

FIG. 6 is a front elevational view of a modified embodiment of that shown in FIG. 1;

FIG. 7 is a right side elevational view thereof;

FIG. 8 is a top plan view thereof;

FIG. 9 is a rear elevational view thereof;

FIG. 10 is a bottom plan view thereof;

FIG. 11 is a front elevational view of a modified embodiment of that shown in FIG. 1;

FIG. 12 is a right side elevational view thereof;

FIG. 13 is a top plan view thereof;

FIG. 14 is a rear elevational view thereof;

FIG. 15 is a bottom plan view thereof;

FIG. 16 is a front elevational view of a modified embodiment of that shown in FIG. 1;

FIG. 17 is a right side elevational view thereof;

FIG. 18 is a top plan view thereof;

FIG. 19 is a rear elevational view thereof; and

FIG. 20 is a bottom plan view thereof.
